US00D982582S

(12) **United States Design Patent** (10) Patent No.: **US D982,582 S**
Wang et al. (45) Date of Patent: ** Apr. 4, 2023

(54) **BODY OF A SMARTWATCH**

(71) Applicant: **BEIJING XIAOMI MOBILE SOFTWARE CO., LTD.**, Beijing (CN)

(72) Inventors: **Hongwei Wang**, Beijing (CN); **Ningning Li**, Beijing (CN); **Tao Wang**, Beijing (CN)

(73) Assignee: **BEIJING XIAOMI MOBILE SOFTWARE CO., LTD.**, Beijing (CN)

(**) Term: **15 Years**

(21) Appl. No.: **35/512,967**

(22) Filed: **Sep. 24, 2021**

(80) **Hague Agreement Data**

Int. Filing Date: **Sep. 24, 2021**

Int. Reg. No.: **DM/217289**

Int. Reg. Date: **Sep. 24, 2021**

Int. Reg. Pub. Date: **Nov. 19, 2021**

(30) **Foreign Application Priority Data**

Mar. 25, 2021 (CN) 202130164720.2
